UNITED STATES PATENT OFFICE.

CORDON ROBERT AVERY, OF LA GRANGE, ILLINOIS, ASSIGNOR TO WESTERN ELECTRIC COMPANY, INCORPORATED, OF NEW YORK, N. Y., A CORPORATION OF NEW YORK.

STRAND-TENSION-CONTROL MECHANISM.

Application filed April 28, 1924. Serial No. 709,332.

This invention relates to strand working mechanisms, and more particularly to tension control mechanisms therefor, which serve to maintain a strand under a substantially uniform tension as it is withdrawn from a supply spool.

An object of this invention is to maintain a strand under a substantially uniform tension as it is withdrawn from a supply spool, 10 in spite of the varying diameter and weight of the spool, inertia at starting, momentum at stopping, and the intermittent, irregular or jerky speed at which the strand is being withdrawn therefrom, without stretching or 15 breaking the strand or injuring the coating, covering, or insulation thereof.

Another object of this invention is to provide a stranding machine with an improved mechanism for automatically maintaining 20 the strands under a practically uniform tension as they are unwound from the supply spools.

Other objects and advantages of the present invention will become apparent in the 25 following detailed description, and will be particularly pointed out in the appended claims.

For convenience throughout the specification and claims, the word "strand" will be 30 taken to include any elongated material, such as wire, thread, string, rope, ribbon, cable, etc.; and the word "spool" will be taken to include any rotatable object upon which a strand may be wound and from which it may 35 afterwards be unwound.

One embodiment of the invention may comprise a pivotal member carrying a guide roller which is positioned to normally engage the strand, said pivotal member being 40 operatively connected to a friction brake member which normally engages the head of the supply spool. Variations in the tension or pull on the strand are partially taken up by the pivotal guide member which at the 45 same time operates to vary the braking effect of the brake member, thereby varying the speed of the supply spool so as to maintain the tension of the strand substantially uniform.

50 While the invention is herein illustrated and described as applied to a stranding machine, it is apparent that the features thereof are applicable to various other forms of strand working machines without departing

from the general scope of the invention 55 which should be limited only by the scope of the appended claims.

In the accompanying drawings which illustrate one embodiment of the invention,

Fig. 1 is a front elevation, partly in section, of a stranding machine with a tension mechanism embodying the present invention mounted thereon;

Fig. 2 is a fragmentary front elevation of the tension mechanism shown in Fig. 1, and

Fig. 3 is a fragmentary detail view of one of the supply spool heads and a part of the bearing member.

Referring now to the drawings in detail, in which like reference numerals are employed 70 to designate similar parts in all the views, 10 denotes, generally, one unit of a stranding machine, such as is used in the manufacturing of telephone cables. A drum 11 is revolvably journaled in bearings 12 and 13 by hollow end trunnions 14 and 15 respectively. The bearings 12 and 13 are rigidly supported on upright standards 16 and 17 respectively which are reinforced by a cross member 18. Guide rings 19 and 20 are 75 mounted on the drum 11 on opposite sides of the bearing 13 in such a position that the openings therein are in longitudinal alignment with the opening in the trunnion 15. A polisher 21 is supported on a bracket 22 80 secured to the standard 17.

Referring now to Figs. 1 and 3, a pair of annular bands 23, are rigidly supported about the drum 11 and are provided with a plurality of equally spaced bearings 24 in 85 which a plurality of supply spools 25 are revolvably mounted. The periphery of the drum 11 comprises a plurality of equally spaced angle irons 26, there being one for each supply spool. Since the stranding machine disclosed is of a well-known type and forms no part of this invention, it is thought that a further detailed description thereof is unnecessary.

The improved tension control mechanism, 100 which serves to maintain the strand under a substantially uniform tension as it is withdrawn from the supply spool, will now be described; an arm 27, carrying a guide roller 28, is pivoted at 29 to the angle iron 26 and is resiliently connected by a tension spring 30 to the vertical leg of an angular member 31, the other leg of which is pivoted

at 32 to the angle iron 26. One end of a tension spring 33 is pivoted at 34 to the angle iron 26 and its other end is connected to the vertical leg of the member 31. Under normal operating conditions, the resulting effect of the springs 30 and 33 produces a balance between the arm 27 and member 31. A brake member 35 is carried on the lower leg of the member 31 and is provided with a friction brake shoe 36 which is positioned to normally engage one of the heads 37 of the supply spool 25. A suitable stop 38 is provided to limit the movement of the arm 27. Both the arm 27 and member 31 are provided with a plurality of apertures 39 and 40 respectively which serve as adjusting means for properly regulating the tension of the springs 30 and 33.

The operation of the mechanism above described is as follows: The drum 11 is revolved by any suitable source of power (not shown) through gearing indicated at 41. Strands 45, drawn from the supply spools 25, are passed over the guide rollers 28, through the guide rings 19 and 20, and then through the polisher 21, at which point the stranding takes place. Any suitable mechanism, such as a power driven capstan (not shown), may be employed to withdraw the strands from the supply spools and pass them through the above mentioned guide rings and polisher. Since the tension of the spring 33 is greater than the tension of the spring 30, under normal operating conditions the brake shoe 36 constantly engages the head of the supply spool, which, while permitting its free rotation, prevents spinning thereof. By this arrangement any slight variations in the tension or pull on the strand are taken up by the spring 30 without varying the braking effect of the brake shoe 36. However, larger variations in the tension or pull on the strand produce greater unbalances between the springs 30 and 33 so that the arm 31 is caused to swing to the left or right on its pivot 32, thereby increasing or decreasing the braking effect of the brake shoe 36 until the tension of the strand is again restored to normal.

It is apparent from the above description that the mechanism disclosed is simple in construction and in operation and performs the function for which it is intended without in any way stretching or breaking the strand or injuring the coating, covering, or insulation thereof. It should be understood that although the mechanism is disclosed as applied to a stranding machine, the features thereof are applicable to various other forms

of strand working machines and the invention should be limited only by the scope of the appended claims.

What is claimed is:

1. A mechanism for maintaining a substantially uniform tension in a strand being withdrawn from a supply spool, comprising a brake member engaging the face of the spool head, a pivoted lever associated with said brake, two springs connected with said lever and disposed at opposite sides thereof and acting in opposite directions, a sheave over which the strand passes, and pivoted means carrying said sheave and responsive to the tension of the strand for directly acting on one of said springs for varying the position of said pivoted lever and consequently the braking effect of said brake member.

2. A mechanism for maintaining a substantially uniform tension in a strand being withdrawn from a supply reel, comprising a lever arm supporting a brake, resilient means for engaging the brake, an arm actuated by the tension in the strand, and a resilient connection between the arm and the lever tending to communicate the movement of the arm due to the variations in the tension of the strand to the lever engaging the brake.

3. A mechanism for maintaining a substantially uniform tension in a strand being withdrawn from a supply reel, comprising a brake mounted on one end of a lever for controlling the rotation of the reel, a spring attached to the opposite end of the lever for engaging the brake with the reel, a second spring attached to the lever for disengaging the brake, a pivoted arm operatively connected with said lever through said second spring, a sheave carried by said arm for guiding the strand, and a stop for limiting the movement imparted to the arm by the springs.

4. A mechanism for maintaining a substantially uniform tension in a strand being withdrawn from a supply reel, comprising a brake for engaging the supply reel, a lever arm supporting the brake, a spring attached thereto tending to engage the brake with the reel, a pivoted arm, a second spring attached to the lever arm tending to disengage the brake, said second spring attached to and actuated by the pivoted arm, and a sheave over which the strand passes carried by said arm.

In witness whereof, I hereunto subscribe my name this 16th day of April, A. D. 1924.

CORDON ROBERT AVERY.
